UNITED STATES PATENT OFFICE.

EDWIN S. FROST, OF WATKINS, NEW YORK.

GRAIN-BINDER.

SPECIFICATION forming part of Letters Patent No. 280,461, dated July 3, 1883.

Application filed August 7, 1882. (Model.)

To all whom it may concern:

Be it known that I, EDWIN S. FROST, a citizen of the United States, residing at Watkins, in the county of Schuyler and State of New York, have invented a new and useful Improvement in Grain-Binders, of which the following is a specification.

My invention relates to improvements in grain-binders which are adapted for use in connection with harvesters or gleaners, and in which twine is used for the binding material; and my invention relates more particularly to that class of grain-binders in which the knot-tying mechanism is carried by the binder-arm; and the objects of my improvements are to simplify the construction and arrangement of the mechanism which operates the twine grasping, knotting, and cutting devices in their relation to each other, and also the movement of the binder-arm, to insure a positive action of the parts, and thus render their operation effectual and certain. I attain these objects by the mechanism illustrated in the accompanying drawings, in which—

Figure 1 represents a perspective view of the binder-frame to be attached to the side of a harvester. Fig. 2 is a transverse vertical section of the same through the path of the binding-arm. Fig. 3 is a side view of a portion of the machine, showing the twine holding and cutting devices secured thereto. Fig. 4 is a vertical section of the machine through the center of the passage-way provided therein for the binder-arm, showing one side of said passage and an end view of the twine holding and cutting devices. Fig. 5 is a perspective view of one side piece of the binder-arm passage carrying the twine holding and cutting devices, but with these parts removed to show the switch for operating the twine-holder. Fig. 6 shows perspective views of the upper and under side of the shield carrying the track and switch used to operate the twine-cutter. Fig. 7 is a perspective view of the upper side of the pivoted arm carrying the twine cutter and holder. Fig. 7^a is a perspective view of the twine-cutter. Fig. 8 is a perspective view of the under side of the same. Fig. 9 is a perspective of the twine-holder detached. Fig. 10 is a perspective view of the end of the binder-arm carrying the knot-tying mechanism. Fig. 11 is a

top view of the same with the top plate removed. Fig. 12 is a view of the under side of the said top plate. Fig. 13 is a side view, on an enlarged scale, of the binder-arm with the side plate removed. Fig. 14 is a perspective view of the hook used to retain the ends of the twine in forming the knot with its operating rod and lever. Fig. 15 is a perspective view of the swinging arm used to remove the knot from the knotter and force it close to the gavel. Fig. 15^a is a modification of the device to remove the knot from the knotter. Fig. 16 is a perspective view of the pivoted nippers used to carry the twine to the knotting-head. Fig. 17 is a top view of a portion of the shaft operating the grain-feeding fingers and the retracting-spring therefor. Fig. 18 is a transverse section of the binder-arm shaft with the eccentric and lever used to operate the grain-feeding fingers.

In the drawings, A designates the inclined frame usually found in elevated delivery-harvesters to carry the rollers *a* of its elevating-aprons. To the frame are secured the lower sills, A', of the machine, and also at a suitable height the horizontal beams A², carrying the shaft B of the binder-arm B'. When the grain has reached the top of the elevating apron, it is received upon slats *a'*, between which project the fingers *a'*, carried by the roller *a'* to advance the grain toward the binder-arm B'.

Over the feeding-roller *a'* there is placed a similar roller, *a'*, having projecting fingers also to engage the grain and force it against the two arms *c c*, pendent from the horizontal shaft C, these arms holding it until there is enough to make a bundle. Start the machine in operation as follows: To one end of the shaft C there is secured a crank, *c'*, having a crank-pin, *c'*, that enters a slot in one end of a connecting-rod *d*. The opposite end of the rod is connected with a spring-latch pivoted to the frame at *d'*. This latch rests upon the clutch *e*, and keeps its ratcheted face from contact with the ratchet-face forming a part of the pulley B², and consequently retains the shaft B stationary until sufficient grain has collected against the pendent arms *c c* and elevated them, so that the crank-pin *c'* will bear against the outer end of the slot, and pulling the connecting-rod *d* lifts the latch *D* off the seat and permits the clutch *e*, under the

impulse of the spring e' upon the shaft B, to come into mesh with the ratchet upon the pulley B^2 , and thus give motion to the shaft B, the clutch being connected to the shaft by means 5 of a feather and groove, as is common. When the bundle is complete and removed, the shaft B comes again to a stop by reason of the beveled side of the latch D bearing against the projection e^2 upon one side of the clutch and 10 forcing it away from the pulley. This pulley B^2 receives a constant rotary motion from the chain b^2 , leading from the pulley a^5 upon the end of the shaft of the roller a of the elevating-apron of the harvester. This chain gives 15 at the same time a constant rotating motion to the grain-feeding roller $a^3 a^4$ by passing over the pulleys a^5 upon their shaft. As the chain b^2 does not encircle the pulleys a^5 and a^6 , it is retained in close contact therewith by means of 20 tension rollers or pulleys a^7 , mounted upon an arm, A^3 , pivoted at a^8 to one end of the beam A^2 of the frame. The free end of this arm A^3 is kept down by means of a latch, A^4 , bearing upon it, and this latch is pivoted to the frame 25 A at a^9 , so that by partially turning it the arm carrying the tension-pulleys can be rocked and the chain can be loosened and unlinked. Just before the end of the binder-arm is ready to descend and enter the grain received from the 30 feed-roller a^8 , said grain is separated from the grain just elevated and rapidly advanced and compressed against the binding-twine and against the pendent curved arms E by the jointed arms F. These arms F, as well as the 35 arms E, are pivoted at f to light overhanging beams A^5 , secured centrally to and over the frame. While the grain is accumulating upon and in front of the slats a' , the jointed arms F occupy the position shown in Fig. 2, being 40 held so by a spring, f' , upon the shaft F' , (see Fig. 19,) that transmits motion to said arms F; but when, as aforesaid, the end of the binder-arm B' is ready to descend, the cam B^3 upon its shafts (see Figs. 1 and 18) bears upon the free 45 end of the bell-crank lever F^2 , that is pivoted to the frame A^2 at f^2 . The opposite end of this bell-crank lever being connected by means of the rod f^3 with the crank F^3 upon one end of the shaft F' , this shaft is rocked by the 50 action of the cam B^3 striking the bell-crank F^2 , and thus pulling upon its crank F^3 .

To the shaft F' are secured the arms F^4 , and the latter have links F^5 , pivoted at f^5 to the ends of the arms F, opposite the ends that carry 55 the pivoted spring-fingers F^6 . The joint uniting the fingers F^6 to the arms F is the equivalent of a butt-hinge—that is, the fingers and arms will remain extended while advancing the grain, but will be folded back while being 60 retracted to the position shown in Fig. 2. When the finger ends of the arms F are projected outwardly by the cam B^3 , they do not reach quite so far as shown in Fig. 1, they being shown in that figure in an extreme position, to clearly show the parts underneath; but they swing far enough to compress the

grain against the binding-twine, the pendent arms E being locked, while the grain is accumulating against them, by the pins f^6 , projecting from the side of the levers F, these pins 70 becoming engaged under the shoulder E' at the inner end of the arm E.

The frame of the binding portion of the machine has an inclined platform, A^6 , to support the gavel, and through the middle of the platform is cut a passage-way for the point of the binder-arm B' . The sides of this passage-way 75 are formed of metal plates A^7 and A^8 , carrying projections to operate as guides for or to actuate the ends of arms projecting from the shell 80 or casing inclosing the knot-tying mechanism at the extremity of the binder-arm B' , as will be described hereinafter.

Upon an inclined platform, A^9 , set at some distance under the platform A^6 , is mounted the 85 combined twine holding and cutting device G. (Shown in Figs. 3, 4, 7, 7^a, 8, and 9.) It is pivoted to the platform A^9 at g , and its free end projects in the passage-way for the binder-arm, as shown in Fig. 3. It is kept at the upper end of said passage-way by a coiled spring, g^1 , fastened thereto at one end, and having its upper end secured to the frame above at g^2 . This arm G carries a straight blade, h , having its extremity beveled to produce a knife-edge, 90 and inclined to form a draw cut. This blade is slid endwise between guides forming a part of the arm G by a coiled spring, h^1 , having one end secured to a pin, h^2 , projecting laterally from the inner end of the blade h , the other end 95 being attached to a hook, g^3 , projecting from the arm G. The blade h is retracted within the arm by a pin, h^3 , projecting from its surface, sliding against the outer side of a spring-switch, i , pivoted to and located under the cap-plate 100 I. This cap-plate is secured to the platform A^9 over the arm G, and carries a curved track, i^1 , upon the concave surface of which the pin h^3 of the blade h travels, and advances beyond the point of the switch i when the free end of the arm G is retracted to the top of the passage-way 105 by the large coiled spring g^1 . The free end of the arm G is depressed by the side B^4 of the shell, at the end of the binding-arm B' , coming in contact therewith, the portion b^4 of 110 the shell being suitably cut away and bent for that purpose. During the first half of the downward course of the arm G the blade's pin h^3 rides against the outside of the switch i , and is thereby retracted until it reaches the 115 pivot i^1 of the switch. It then drops against the track i^1 , causing the knife to cut the binding-twine that is held in its path by the holder k . This holder k is a small rectangular bar, having a notch upon one side to form a hook, 120 k^1 , adapted to retain the binding-twine. It is held within the arm G, parallel with the cutter h , with a very thin plate, g^4 , between them. This holder k is kept retracted within the arm G by a coiled spring, k^2 , secured thereto at 125 one end, and at the other to a pin, g^5 , secured to the under side of the arm G. It is retained 130

permanently within this arm by a small plate, g^6 , and is forced outward by a pin, k^3 , passing through a slot in said plate g^6 . The holder k is made to project endwise out of the arm G 5 by having its pin k^3 ride over the outer side of a spring-switch, l , Figs. 4 and 5, secured to the side of the passage-way cut in the frame supporting the inclined platform A^9 . The edge of said platform is cut away at l' to permit the pin k^3 to be retracted by the spring k^2 behind the switch l , and thus grab and hold the binding-twine between the hook k' and the notch g^7 in the end of the arm G before the pin k^2 of the cutter has left the face of the 15 switch l , and consequently before said cutter has been projected against the twine by its spring h' .

The blade h may have both of its sides smooth, and operate successfully in connection with the holder; but I prefer to construct it with a notch forming a hook, h^4 , in the side thereof, so that when the cutter-blade is projected to cut the cord it shall receive in the notch the portion of cord held by the cord 20 holder, and this holder being forced out to receive a new end before the cutter-blade is projected to cut the same. This notch in the cutter-blade, by holding onto the end first caught by the holder, will cause it to be surely dropped 25 from the holder notch or hook when it is forced out to catch a new end. To give a side support for the cord while the blade is projected to cut it, the cap-plate g^8 of the arm G is provided with a hook, g^9 , extending beyond the 30 end of said cap-plate to receive and hold the cord in front of the cutting-edge of the blade.

The binding-twine coming from the spool and tension device (not shown in the drawings) passes over or around the guide-pulley 40 a^{12} , pivoted to the frame on top of the machine, thence to the holder k , and being clamped thereby, the machine is in proper condition to operate. The grain fed along by the fingers of the rollers a^3 and a^4 is pushed against the 45 binding-twine and crowds it forward, so that when the end of the binder-arm comes down the twine extending from the pulley a^{12} to the holder enters the slot m in the top plate, M , of the casing in the end of the binding-arm, and 50 carries it down around the gavel to the arm G , containing the holder and cutting-blade, where it is first grasped and then cut, the roller n on the needle pushing the cord behind the hook k' of the holder; but before the cord is cut its 55 two ends have been seized by the spring-nippers N , carried by the binder-arm, as will be hereinafter described, the cord being guided between the jaws of the nippers by the beveled or inclined plate O on the side of the needle-frame. These nippers have a rigid jaw, N' , 60 pivoted to the needle at n' , and a jaw, N^2 , pivoted to the jaw N' at n^2 , the two jaws being kept closed by a spring, n^3 , secured to the jaw N' , bearing against the inner side of the rear 65 end or arm n^4 . The rear extremity of the arm n^4 projects through a segmental opening, b^5 , in

the side plate B^4 of the casing, and is forced inward to open the jaws of the nippers and receive the cord by coming against the projection p , secured to the plate A^7 on the side 70 piece of the passage for the needle, and thus the portion of the cord after it enters the casing is received by the nippers. The binder-arm continuing in its course, the portion of the cord adjoining the holder k enters also the 75 slot m in the top plate, M , of the casing, and is also received by the nippers, the latter thus seizing the cord at two points with the gavel between them. The binder-arm still advancing, the upper portion of the cord comes in 80 contact with the holder k , which, as the arm G is depressed, first seizes it, and then the blade h cuts it at a point between the holder and nippers in the head of the binder-arm, leaving the other part fast in the holder. The 85 grasping end of the nippers holding the cord are then carried up near to the head of the revolving hook q of the knot-tyer Q by the arm N^3 , attached to the outer end of the pivot n' of said nippers, its roller n^5 passing in the 90 rear of the projecting track n^4 , secured to the side plate A^8 of the passage-way, and after passing this track the nippers are restored to the position shown in Fig. 13, by the spring n^6 (shown in Fig. 10) pressing under the arm N^3 . 95

To bring the band between the knotting-hook q and the conical end of its tube, guides and latches are secured to the plate M of the knotter-casing and to the sides of its passage-way, as follows: To the under side of this plate 100 M (shown in Fig. 12) is pivoted the latch m' upon one side of the slot m , to close the inner end of the latter after the ends of the cord have entered the opening M' in said plate, the spring m^2 pressing against the side of said latch, and 105 the cord is prevented from going too far in the opening M' by an arm, m^3 , pivoted to the top of the plate M at m^4 . A spring, m^5 , pressing against its end m^6 , adjoining its pivot m^4 , causes its end m^7 to press against and be 110 locked by the spring-latch m^8 , pivoted at m^9 , said latch being so locked by having its end m^6 come in contact with the projection m^{10} on the end of side plate A^7 . The latch m^8 releases it at the time the knot is nearly completed by 115 having its end m^{10} , that projects over the edge of the plate M , coming in contact with the pin m^{12} on the side A^8 of the binder-arm passage-way. The arm m^3 , its spring m^5 , and the latch m^8 , with its spring, would in practice be 120 placed under the top plate, M , to protect them from contact with the straw. The ends of the cord are also forced sidewise against and within the hook q of the knot-tyer by the arm R , pivoted to the frame at r and lying across the 125 passage-way of the binder-arm, with its guiding-notch r^2 in or near the middle thereof. The arm is brought to a horizontal position across said passage-way by the spring r' pressing upon its inner end. Its other end is kept 130 locked, except at the time the binder-arm B' passes it, by means of a spring-latch, R^2 , piv-

oted to the frame at r^3 , and this latch is retracted by the side of the plate M coming in contact with its side arm, r^4 .

The cord surrounding the gavel has its two ends retained by the nippers N after passing through the opening between the end of the latch m^1 and the arm m^3 in a position close to the knot-tyer Q, so that when hook q , occupying the position shown in Fig. 11, revolves, it carries with it the two strands of the band once around the knot-tying head, and then the hook q closes upon the strands at the point nearest to the nippers and pulls them through the loop lying around the head in the ordinary manner of this class of knot-tying devices, the nippers releasing the ends of the cord by having their arm n^1 coming in contact with the projection n^1 on the side plate A^7 of the passage-way. To revolve the knotter Q, there is mounted thereon a pinion, Q' , adapted to mesh with a rack, Q^2 , secured to the side plate A^8 of the passage-way; and to stop the momentum of the pinion as soon as it has made a revolution, there is a spring-pawl, s , made to engage with the teeth of the pinion. This pawl is pivoted to the frame B^6 of the knotter frame or easing at s' , its spring s^2 keeping it in engagement with the pinion except when the outwardly-projecting end s^3 of the pawl bears against the projecting track Q^3 located under and following the rack Q^2 .

The knotter-hook q has its inner end pivoted to the rod q^2 , having one end formed with a head, q^3 , that is received between the prongs of its operating-lever q^4 . This lever is pivoted at q^5 , about the middle of its length, to the frame B^6 of the binder-arm. Its other end is forced outward by a spring, q^6 , and it carries a roller, q^7 , adapted to travel upon the raised track A^{12} , secured to the frame in the lower portion of the passage-way to pull the rod q^2 and complete the knot.

To remove the knot from the knotter-head and tighten it as close to the bundle as possible, there is within the easing an arm, T, pivoted to the frame B^6 at t , so that its extremity T' can be elevated. For this purpose, its pivot or axle t is provided with an arm, T^2 , carrying at its end a roller, t^2 , that is depressed by coming in contact with the projection t^3 upon the plate A^8 of the passage-way at the moment the knot is removed from the knotter; otherwise the arm T^2 is kept elevated by the spring t^4 pressing under it. The end T' of the arm T in Fig. 15 is concave to embrace one side of the knotter-shank, and it carries a horizontally-swinging arm, T^3 , having a perforation, t^5 , which encircles the shank of the knotter-head. This arm T^3 is pivoted to the arm T at t^6 , and is made to bear sidewise against the knotter-head, and tightens the knot by a spring, t^7 , the length of oscillation of said arm T^3 being limited by the pin t^8 , projecting from the arm T. This knot-removing device is practically effective; but the action of the spring t^7 being somewhat sudden, I prefer the

construction shown in Fig. 15^a, in which there are standing up from the top of the frame B^6 two guide-rods, u and u' , having their upper ends bent in opposite directions, and between 70 these rods are placed upon the arm T two plates, T' and T^3 , retained connected to the arm T by pins t^9 , passing loosely through slots in the plates T' and T^3 . The plate T' has its end concave to bear against one side of the 75 knotter-shank, and the plate T^3 has an opening, t^5 , the interior surface of which bears against the opposite side of the knotter-shank. These plates have grooves u^2 in the sides to receive the guides u and u' ; and it is evident 80 that when the free end of the arm T is elevated and brings the grooves u^3 against the curved faces of the guide-rods u u' , the plates T' and T^3 will be moved in opposite directions. The grooves u^2 are shown as cut from the sides of 85 the plates T' and T^3 ; but they may be cut from the center of the plates by having the curved guide-rods u u' secured to the frame B^6 in a position corresponding therewith.

Upon one side of the knotter-inclosing eas- 90 ing or frame there is a friction-roller, t^4 , to guide the binder-arm against the side plate A^8 of the passage-way. While the machine thus binds the gavel, the latter is supported by the spring-arms V on each side of the path of the 95 binder-arm. They are pivoted to the frame at v , and to their heels is attached the coil-spring v' , having its lower extremity secured to the cross-beam of the frame. After the gavel is bound it is ejected or delivered from 100 the binder-arm either by its own momentum and weight or by an arm upon a rock-shaft, or by other suitable means.

The same binding-arm, with its cord holding and tying mechanism, may be made to operate 105 with a gleaner and revolve in the opposite direction from the one above described by inverting and changing from one side to the other the side plates, A^7 A^8 , of the passage-way as well as the cord-holder and cutting-blade. 110

Having now fully described my invention, I claim—

1. In a grain-binding machine having a revolving binder-arm carrying the knotter, the combination of the shaft B of the binder-arm, 115 the driving-pulley B^2 , loose thereon and provided with a ratehet-face, and a spring-clutch splined upon said shaft, with a spring-latch lying normally between said pulley and spring-clutch, a connecting-rod, d , and a crank-shaft 120 having pendent arms e , substantially as and for the purpose described.

2. The combination of a shaft, B, having a binder-arm carrying the knotter, a cam, B^3 , upon said shaft, a bell-crank lever pivoted to 125 the frame and operated by the cam B^3 , a connecting-rod, and a crank-shaft, F', having arms F^4 , connected to jointed arms F^4 F^5 , pivoted to the frame, substantially as and for the purpose set forth.

3. The combination of a shaft, B, having a 130 binder-arm carrying the knotter, a cam, B^3 ,

upon said shaft, a pivoted bell-crank lever operated thereby, a connecting-rod, crank-shaft F', having arms F⁴, connected to jointed levers F F⁶, having pins f⁶, and pendent pivoted arms E, substantially as and for the purpose described.

4. The combination of a shaft, B, having a binder-arm carrying the knotter, with grain-feeding rollers a³ and a⁴, having fingers a², slats a', and inclined platform having cut centrally therethrough a passage-way to form a path for said binder-arm, with gavel-supporting arms V, having a spring at their inner end, substantially as and for the purpose described.

15 5. The combination of a revolving binder-arm carrying the knotter, and an inclined platform on the under side of the grain-table and lying to one side of the binder-arm path, with an arm, G, pivoted to said platform and carrying a sliding cord-holder and a sliding cutting-blade, and projecting into the passage-way cut in the grain-table, substantially as and for the purpose described.

6. The combination of a revolving binder-arm carrying the knotter, a platform or support on the under side of the grain-table and to one side of the binder-arm path, an arm, G, pivoted to said platform and projecting into the passage-way cut in the grain-table, and a 25 spring-actuated cutting-blade adapted to slide endwise in said arm, and having a projecting pin, h³, with a cap-plate, I, having a curved track and a spring-switch to guide and retract the blade, substantially as and for the purpose described.

30 7. The combination of the arm G, carrying a spring cord-holder, k, adapted to slide endwise in said arm, with a cutting-blade adapted to slide in said arm parallel with the holder, and a cap-plate, g⁸, provided with a hook, g⁹, extending over the cutting-edge of the blade, the holder and cutter being provided with operating-pins extending through the cap-plate, substantially as and for the purpose described.

45 8. The combination of a revolving binder-arm carrying the knotter, an arm, G, pivoted to the frame and having its extremity projecting into the path of said binder-arm, and a cord-holder, k, adapted to slide in the arm G 50 and carrying a projecting pin, k³, with a spring-switch, l, pivoted to the side of the binder-arm passage-way to project the cord-holder from its carrying-arm, substantially as and for the purpose described.

55 9. The combination of a revolving binder-arm carrying the knotter, a pair of spring-nippers pivoted to the knotter-carrying frame or casing on the end of the binder-arm, and having an arm, N³, in the rear thereof, and a rearwardly-projecting arm, n⁴, with a projection, p, on the side of the binder-arm passage-way to bear against the end of the arm n⁴ of the pivoted spring-nippers and open the nipper-jaws, substantially as and for the purpose described.

10. The combination of a revolving binder-arm carrying the knotter, an arm of a pair of spring-nippers pivoted to the knotter-carrying frame or casing on the end of the binder-arm, and having its jaws adapted to swing into close proximity to the knotter-head, and an arm, n⁴, of the pivoted jaw N², projecting from the knotter frame or casing, with a projection, n⁷, on the side of the binder-arm passage-way to open the nipper-jaws and release the ends 70 of the binding-cord, substantially as described.

11. The combination of a revolving binder-arm carrying the knotter, the plate M of the knotter frame or casing having an opening and a slot for the passage of the binding-cord, 80 and a latch, m', to close said slot, with an arm, m³, and latch m⁸, and their operating projections m¹² m¹³ upon the sides of the binder-arm passage-way, substantially as and for the purpose described.

12. The combination of a revolving binder-arm carrying the knotter, an inclined platform having a passage-way cut therethrough for the passage of said binder-arm, and an arm, R, extending across said passage-way 90 and pivoted on one side thereof, with a spring-latch, R², on the opposite side, released by the binder-arm, substantially as and for the purpose described.

13. The combination of a revolving binder-arm carrying the knotter-inclosing casing or frame, and a knot stripping and tightening arm T, pivoted to said frame, with sliding plates connected to said arm and adapted to bear in opposite directions against the knotter-shank and guide-rods u and u', secured to the knotter-frame, and having their free ends curved in opposite directions, and mechanism for operating the stripper, substantially as and for the purpose described.

100 14. The combination of a revolving binder-arm and knotter-carrying casing or frame, and a knot stripping and tightening arm, T, pivoted to said frame, and carrying a plate, T³, perforated to surround the knotter-shank, 110 with an arm, T⁴, mounted upon the axle of the arm T, and a projection, t³, upon the side of the binder-arm passage-way, substantially as and for the purpose described.

15. The combination of a revolving binder-arm and the frame carrying the knotter, a pair of spring-nippers pivoted to said frame, and having its jaws adapted to swing into close proximity to the knotter-head, and an arm, N³, secured to the pivot of said nippers, and having a friction-roller at its extremity, with a projecting track, N⁴, on the side of the binder-arm passage-way, substantially as and for the purpose described.

EDWIN S. FROST.
